DESIGN FOR A MEDICINE CABINET OR THE LIKE

Kenneth S. Adams, Bartlesville, Okla., assignor to Phillips Petroleum Company, a corporation of Delaware

Application May 16, 1944, Serial No. 113,622

Term of patent 14 years

(Cl. D80—5)

To all whom it may concern:

Be it known that I, Kenneth S. Adams, a citizen of the United States, a resident of Bartlesville, in the county of Washington and State of Oklahoma, have invented a new, original, and ornamental Design for a Medicine Cabinet or the like, of which the following is a specification, reference being had to the accompanying drawing, forming part thereof.

Figure 1 is a front perspective view of the medicine cabinet or the like, showing my new design, the front door element being shown in its closed position.

What I claim is:

The ornamental design for a medicine cabinet or the like, as shown and described.

KENNETH S. ADAMS.
